UNITED STATES PATENT OFFICE.

MARK H. MILLER, OF CLAREMONT, SOUTH DAKOTA.

REFRIGERATOR.

Application filed May 25, 1922. Serial No. 563,654.

To all whom it may concern:

Be it known that I, MARK H. MILLER, a citizen of the United States, residing at Claremont, in the county of Brown and State of South Dakota, have invented certain new and useful Improvements in Refrigerators, of which the following is a specification.

My invention relates to refrigerators or coolers for meats and vegetables and has for its object to provide a device of this character, using flowing water as the cooling medium instead of ice.

The cooler is primarily intended for use on farms and country places where artesian wells are prevalent and the supply of ice is limited, but it may also be used by town households when the city water may be led into the cooler. It will, however, be found to be most economical for the farmers and country folks as the artesian well water generally is many degrees cooler than the city water.

One advantage of the device is that the cooler forming the subject-matter of this invention will be more roomy than the ordinary refrigerator as the interior thereof will not be encumbered by the housing of ice.

In the accompanying drawings one embodiment of the invention is illustrated—

Figure 1 shows a top plan view of a cooler;

Figure 2 is a front elevation;

Figure 3 is a horizontal section on the line 3—3 of Figure 2;

Figure 4 is a vertical section on the line 4—4 of Figure 1;

Figure 5 is a horizontal section of a cooler having cylindrical form.

The cooler is constructed in the shape of a cylindrical or semi-cylindrical cabinet open at its flat or front side. It has an inner wall 10 and a jacket 11 surrounding the same and spaced therefrom to provide a water chamber 12. This chamber 12 runs from the top to the bottom of the cabinet which is closed at the upper end by a double walled top 13 composed of a pair of spaced plates between which preferably heat-insulating material 14 is enclosed. In the middle of the top is provided a vent 15 which may be closed by a cover 16. The bottom 17 is constructed in the same manner by two spaced plates with heat-insulating material 18 between them and provided in the middle by a drain opening 19. Instead of filling the

top and bottom with the heat-insulating material, the open space may communicate with the chamber 12 so that the cooled water may circulate not only through the side walls 60 but also through the top and bottom of the cabinet.

A door 20 also constructed of spaced plates to form a chamber 21 filled with a heat-insulating material is adapted to close the 65 front opening of the cabinet, as seen in Figure 3, and fitting between posts 23 on either side of the door. This door is hinged, as at 24, and has a lock 25 on the opposite side.

At 26 is formed an outlet opening with 70 a pipe for leading away the water from the cabinet, and at 27 is another opening connected by means of a pipe with a cold water supply for the chamber 12. In Figures 2, 75 3 and 4, these inlet and outlet openings have been shown, respectively, at the bottom and top of the cabinet which will be used when the water is forced in under great pressure. Should, however, high pressure water not be available, the inlet and outlet openings 80 may be reversed or both placed at the top or both at the bottom of the cabinet as most suitable for local conditions.

Referring particularly to Figure 4, shelves 85 30 are provided within the cabinet. Both of these shelves are shown as gratings in this figure.

Instead of constructing the cabinet, as best seen in Figures 1 and 3, with the semi-cylindrical back and substantially straight 90 side walls, I may construct the cabinet in substantially cylindrical form, as seen in Figure 5, where an opening is provided at one side of the cabinet much narrower than is the case in the cabinet, shown in Figures 95 1, 2, 3 and 4, and this opening will then be closed by a flat or curved door portion 31 which, in the latter case, would complete the cylinder. This door is constructed of two plates in the same manner as the 100 door 20 and filled with heat-insulating material.

The cabinet may preferably be raised from the ground and placed on feet 32.

It will be readily understood that the 105 temperature in the cabinet will be kept very low by the circulation of the cold water through it and that the temperature will be more even than what is possible with an ice-cooled refrigerator where a considerable 110 difference of temperature is experienced if the ice chamber is filled or nearly empty.

On the other hand, the temperature of the water is the same all the time and the same quantity filling the water jacket 12 will make the temperature in my cabinet practically constant and it may, of course, be moderated by stemming the system of water by means of a cock 33 or the like in case the temperature within it is found too low.

In some cases, it may be advisable to partly fill the chauber 12 of the cooler with such heat-insulating material as cork, felt, asbestos and the like and to permit the water to circulate through the partitioned off spaces. This would be particularly advantageous in case some of the contents of the cabinet required less cold temperature than others.

In this manner also, a more circuitous passage for the water may be provided so that the heat of the cooler may be taken up and carried away by the water as completely as possible.

It will be evident that, instead of building the cooler in the forms shown on the drawings, that is, of cylindrical or semi-cylindrical shape, it may be built with a square, rectangular, hexagonal or any other suitable cross section.

Having thus described the invention, what is claimed as new is:

A cooler comprising a cabinet having a food compartment provided with inner and outer walls disposed in spaced relation to provide a compartment between the walls adapted to receive a cooling medium, a top closing the upper end of said food compartment and having a marginal portion secured to the upper ends of said inner and outer walls and closing the upper end of the space between the inner and outer walls, a bottom for said food compartment closing the lower end thereof and secured to the lower end of the inner wall and having a marginal portion extending across the space between the inner and outer walls and secured to the outer wall, and supporting legs extending downwardly from said outer wall and having portions extending upwardly and inwardly from their lower ends and engaging said bottom beneath the inner wall and adapted to support the bottom and inner wall.

In testimony whereof I affix my signature.

MARK H. MILLER. [L. S.]
